PLASTIC FEEDING TUB FOR ANIMALS

Robert D. Moore, 1810 Melhill Way, Los Angeles, Calif.

Filed Sept. 9, 1964, Ser. No. 81,662

Term of patent 14 years

(Cl. D12—2)

FIG. 1.

FIG. 2.

FIG 3.

FIG 4.

FIG. 1 is a view in perspective of a plastic feeding tub for animals showing my new design.

FIG. 2 is a view in elevation of the same.

FIG. 3 is a top plan view of the same.

FIG. 4 is a bottom plan view of the same.

I claim:

The ornamental design for a plastic feeding tub for animals, substantially as shown.
